(57) **CLAIM**

The ornamental design for a sloped wireless sensor system, as shown and described.

DESCRIPTION

FIG. 1 is a perspective view of a sloped wireless sensor system of the new design;

FIG. 2 is a top view of the sloped wireless sensor system of FIG. 1;

FIG. 3 is a bottom view of the sloped wireless sensor system of FIG. 1;

FIG. 4 is a front view of the sloped wireless sensor system of FIG. 1;

FIG. 5 is a rear view of the sloped wireless sensor system of FIG. 1;

FIG. 6 is a left side view of the sloped wireless sensor system of FIG. 1; and,

FIG. 7 is a right side view of the sloped wireless sensor system of FIG. 1.

The broken lines depict unclaimed portions of the sloped wireless sensor system and form no part of the claimed design.
